UNITED STATES PATENT OFFICE.

ADOLF PROBST, OF HESSENTHAL, NEAR HALL, GERMANY.

FLOOR AND CEILING.

SPECIFICATION forming part of Letters Patent No. 772,372, dated October 18, 1904.

Application filed February 23, 1904. Serial No. 194,838. (No model.)

To all whom it may concern:

Be it known that I, ADOLF PROBST, manufacturer, a subject of the King of Würtemberg, residing at Hesenthal, near Hall, in the 5 Kingdom of Würtemberg, Germany, have invented certain new and useful Improvements in Floors and Ceilings; and I do hereby declare the following to be a full, clear, and exact description of the invention, such as will 10 enable others skilled in the art to which it appertains to make and use the same.

The object of the present application consists of an improved wood beam flooring or ceiling possessing the same advantages as floors 15 or ceilings of hollow-stone slabs—namely, that it is dry, forms great protection against fire, is a bad conductor of sound and of heat, and can be rapidly constructed, while obviating the drawbacks of the aforesaid hollow-stone 20 floors, which are principally that the slabs have too small a bearing capacity to be able to serve as protective supports and that the nailing at the nail-holes often causes the splitting of the said slabs. These drawbacks are 25 obviated in the present invention by securing cross-beams in any suitable manner to the under side of the supporting floor-beams and arranging the hollow slabs in the spaces between the floor-beams and resting upon the 30 cross-beams. In consequence of the support by means of the cross-beams the slabs can be provided with particularly large hollow spaces, which reduces the quantity of material required and increases their resistance to sound. 35

In Figures 1 to 4 two constructional modifications of a flooring of this kind are illustrated, and Fig. 5 shows a detail thereof.

In the drawings, *a* denote the floor-beams, to the lower sides of which are secured the 40 cross-beams *b*, consisting either of wood planks or of angle-irons lined with wood in the well-known manner. The latter support the ceiling-slabs *c*, which are arranged between the beams and provided with hollow spaces to 45 diminish the weight and the lower edges of which are provided with grooves *d* for the reception of the cross-beams. The latter lie with their lower sides in the same plane as the lower sides of the ceiling-slabs *c* in such 50 a manner that the lathing or the like which

supports the plastering or other finishing-surface can be attached immediately to the cross-beams. In addition the cross-beams serve also as closing-pièces for the apertures between the separate slabs, which spaces can be 55 filled with liquid cement or the like.

Fig. 3 shows a view from above of one mode of construction. In this the ceiling-stones *c* are scalloped or provided on their longer side with wave-shaped projections, already 60 well-known in connection with ceiling-slabs, or they are provided with projections or the like which engage in the interstices of the projections of the adjacent slabs. This arrangement has for its object to assist the cross-beams *b* in supporting the ceiling-slabs by means of a wire *e*, as shown in Figs. 4 and 5, which wire is carried along the medial line of the cross-beam *b* and fixed in any convenient manner to the cross-beam *a*. 70

In the form illustrated in Fig. 4 the wire passes over or around the beam and is held fast at the angles with clamps or the like. This wire is so held by the intermeshing wave-shaped projections of the ceiling-slabs, 75 as shown in Fig. 3, that a wire at the same time supports two slabs resting upon a cross-beam, and so relieves the pressure upon the said cross-beam, wherefore it would be of great advantage in the event of the weakening of a cross-beam in the case of fire or from other cause. Moreover, with this form of the slabs the joints are filled with gypsum, cement, or the like, which completely surrounds and embeds the wire *e*. One can, 80 moreover, in addition to the special groove for the cross-beams, provide a special groove for the wire, so that the slab will have the sectional shape illustrated in Fig. 5. The floor to be secured above the ceiling can be 85 90 of any desired construction.

What I claim, and desire to secure by Letters Patent, is—

1. In a floor or ceiling, supporting-beams, cross-beams supported thereby and slabs having intermeshing edges resting upon the cross-beams and extending in the same general direction. 95

2. In a floor or ceiling, supporting-beams, cross-beams secured to the under side there- 100

of, and slabs having intermeshing edges resting upon the cross-beams and breaking joints therewith.

3. In a floor or ceiling, supporting-beams, 5 cross-beams supported thereby, and slabs having intermeshing escalloped edges resting upon the cross-beams and breaking joints therewith.

4. In a floor or ceiling, supporting-beams, 10 cross-beams secured to the under side thereof, and slabs resting upon the cross-beams and breaking joints therewith, the slabs having escalloped edges adapted to intermesh and being undercut at the edge to form the 15 half of a groove for the reception of the cross-beams.

5. In a floor or ceiling, supporting-beams, cross-beams secured to the under side thereof and slabs resting upon the cross-beams and 20 breaking joints therewith, the slabs having escalloped edges adapted to intermesh and being undercut at the edge to form the half of a groove for the reception of the cross-beams.

6. In a floor or ceiling, supporting-beams, 25 cross-beams secured to the under side thereof, wires secured to a fixed support and extending longitudinally of the upper side of the cross-beams, and slabs resting upon the cross-beams and wires.

30 7. In a floor or ceiling, supporting-beams, cross-beams secured to the under side thereof, wires secured to the beams and extending longitudinally of the upper surface of the

cross-beams, and slabs having intermeshing escalloped edges resting upon the cross-beams 35 and wires and breaking joints therewith.

8. In a floor or ceiling, supporting-beams, cross-beams secured thereto, wires secured to the beams and extending along the medial line of the upper surface of the cross-beams, 40 slabs resting upon the cross-beams and breaking joints therewith, the slabs having their adjacent faces escalloped and intermeshing and their longitudinal edges undercut to form the half of grooves for the reception of the 45 wires and cross-beams.

9. In a floor or ceiling, supporting-beams, cross-beams secured thereto, wires secured to the beams and extending longitudinally of the upper surface of the cross-beams, hollow 50 slabs extending longitudinally of the cross-beams and breaking joints therewith, each of the slabs having escalloped edges adapted to intermesh with those of the adjacent slab and having its longitudinal lower edges undercut 55 to form the half of two grooves, one to receive the wire and one the cross-beams, and the spaces between adjacent slabs being filled with cement.

In testimony whereof I affix my signature to 60 this specification in the presence of two witnesses.

ADOLF PROBST.
